UNITED STATES PATENT OFFICE.

LEE S. CHADWICK, OF SHAKER HEIGHTS VILLAGE, AND MARC RESEK, OF CLEVELAND HEIGHTS, OHIO, ASSIGNORS TO THE CLEVELAND METAL PRODUCTS COMPANY, OF CLEVELAND, OHIO, A CORPORATION OF OHIO.

OIL-BURNER CONSTRUCTION.

Application filed October 26, 1922. Serial No. 596,970.

To all whom it may concern:

Be it known that we, LEE S. CHADWICK and MARC RESEK, citizens of the United States, residing at Shaker Heights Village 5 and Cleveland Heights, respectively, in the county of Cuyahoga and State of Ohio, have invented a certain new and useful Improvement in Oil-Burner Constructions, of which the following is a full, clear, and exact description, reference being had to the accompanying drawings.

This invention relates to improvements in oil burners, especially of the tubular type, and more particularly as said improvements 15 pertain to the wick raising mechanism. Embodiments of the invention are disclosed but not claimed in the applications of Lee S. Chadwick, Serial Nos. 528,813 and 541,898, filed January 12, 1922, and March 8, 20 1922, respectively.

The objects of the invention are to provide wick raising mechanism for oil burners which permits of easy insertion and removal of the wick; which automatically assumes 25 positive connection with the wick when the latter is inserted in the burner and the mechanism actuated to retract the wick; which likewise releases the wick when the latter is fully projected by said mechanism; 30 to provide a burner construction which insures easy action of the wick and wick carrier by properly guiding them within the burner, thereby preventing binding or undue friction and assuring accurate positioning of the top of the wick with respect to 35 the upper ends of the wick tubes; which readily adapts itself to slight variations in the sizes of wick carriers; wherein practically all parts are made of die-formed 40 sheet metal stampings promoting lightness, durability, accuracy and economy; and to so form said parts as to facilitate assembly, expedite manufacture and accordingly effect a comparatively low production 45 cost.

A further object of the invention is to provide a tubular oil burner wherein the inner wick tube has a lateral extension through which exteriorly operated means 50 acts to raise and lower the wick, said lateral extension projecting only a comparatively short distance into the central space enclosed by the burner so as to leave said

space unobstructed for the accommodation of appurtenances such as the air distributing member or flame spreader, latch mechanism therefor, and wick stop mechanism. 55

Another object attained through the making of the lateral extension of the inner wick tube relatively slight is the production of a substantial inner tube that will retain its shape during the assembling of the burner and impart rigidity to the completed burner structure. 60

A still further object is to provide a 65 burner of the above nature wherein the wick raising mechanism is situated well to one side of the central space enclosed by the burner, for the reasons already related, and yet wherein it has connection with the tubular wick at substantially diametrically opposite points, thus assuring an even lifting and perfect action of the wick and avoiding any tendency for it to tilt which might cause it to bind within the wick space. 70

Another object is to utilize the lateral extension of the inner wick tube as a guide for the rod which operates inside it and has operative connection with the wick, and for the channel shaped member which embraces 80 it exteriorly and has connection with the upper end of the rod and through which the rod is operated.

Further objects, which have to do more particularly with structural refinements, 85 will become apparent as this description proceeds.

In the drawings, Fig. 1 is a central vertical sectional view through a burner embodying our invention and equipped with a flame spreader and drum, only the lower part of the latter being included, and the wick being shown as retracted below burning position; Fig. 2 is a sectional view through the burner substantially on the line 2-2 of Fig. 1 and looking in the direction indicated by the arrows associated with said line; Fig. 3 is a section on the line 3-3 of Fig. 2, the wick and certain of the other parts below the plane of section being omitted; Fig. 4 is a fragmentary top plan view, and Fig. 5 a similar bottom plan view, of the burner; Fig. 6 is a perspective view of some of the parts of the wick raising mechanism; Fig. 7 is a similar view of parts 100 shown in Fig. 6, in separated condition; 105

Fig. 8 is a sectional detail showing the wick fully projected and released; Figs. 9 to 18 show modifications of the wick grip.

The burner, generally, is designated A, 5 and in Fig. 1 it is shown as equipped with an air distributing member or flame spreader B, and a drum C.

The air distributing member or flame spreader forms no part of our present invention, and for a full and complete disclosure of the same reference may be had to the application of Lee S. Chadwick, Serial No. 571,671, filed June 29, 1922; and the latch mechanism for locking the flame spreader to parts of the burner is covered in our joint application Serial No. 528,833, filed Jan. 12, 1922. The drum C, with its means of support and connection with the burner, is shown in the application of Lee 15 S. Chadwick, Serial No. 539,079 filed February 25, 1922.

The burner A comprises inner and outer wick tubes 1 and 2, respectively, which are joined together at their lower ends by an 20 annular wall 3 which is formed, in the present instance, by an integral part of the outer wick tube. The tubes 1 and 2 and wall 3 enclose a wick space 5 to which oil is supplied through the usual fitting 6. The foregoing parts in general, are common to well 25 known types of tubular burners; but to adapt the structure to our present improvements, the inner wick tube 1 is formed substantially heart shaped, as most clearly 30 shown in Fig. 3, to provide a restricted offset portion 8 which opens into an enlargement 9 of the wick space 5. The offset portion 8 is comparatively shallow in a radial direction so as not to obstruct the central 35 portion of the space enclosed by the burner and which is occupied by wick stop mechanism hereinafter referred to. Within the 40 enlargement 9 of the wick space is guided a wick elevator or yoke 10 having side branches 11 that extend about the wick space and terminate in angular extensions 12 at 45 substantially diametrically opposite points of the wick space. The yoke 10 is preferably formed of sheet metal, and to give it rigidity is reinforced on its under side by a 50 stiffener 13 of substantially the same shape as the yoke. Said stiffener has a segmental horizontal wall 14 which is soldered or otherwise secured at its edge to the edge 55 portion of the yoke, and a vertical wall 15 which follows the general contour of the inner side of the yoke and is secured to the yoke through lugs 16 that are turned down 60 over the outer side of the wall 15, said lugs, and the meeting edge portions of the wall 15 and yoke, being soldered or otherwise 65 secured together. The yoke, as thus formed, includes an arm 17 which enters the previously mentioned restricted offset portion 8; 70 and to maintain the arm centrally within

the offset portion and to properly guide it during its vertical movement therewithin, the wall 15 has lugs 18 projected outwardly therefrom for sliding engagement with the opposite walls of the offset portion 8. The 75 inner wick tube has ribs 19 between which and the opposite surface of the outer tube the wick elevator or yoke 10 is freely movable; and the outer wick tube is provided with ribs 22 for guiding the wick and its carrier properly within the wick space and reducing their frictional contact with the outer tube. In referring to this feature of the invention we call attention to its distinctions and advantages over well known 80 prior forms of wick guiding means such, for instance, as when the wick rides upon and is guided solely by the inner tube, with the wick carrier situated on the outer side of the wick, and wherein there is more or less binding and tilting of the wick, making the raising and lowering of the wick difficult and resulting in an uneven flame; where the wick, equipped with a perforated carrier, is 85 raised and lowered by star wheels or pinions meshing with the perforations of the carrier and wherein the carrier and wick are guided between ribs on the inner and outer tubes in the vicinity of the star wheels or pinions, or between said wheels or pinions and ribs on the inner tube, in either of which cases the wick and carrier are supported and actuated at one side which, especially when carbon 90 accumulates on the wick, is apt to cause the wick to tilt and bind; and when the wick and carrier fit loosely between the wick tubes and are lifted by a suitable member 95 from below, in which construction there is a tendency for the wick to wobble because of its looseness and this results in an uneven flame and in the wick not being properly centralized within the wick space. 100

It will be readily seen that these difficulties are obviated in our construction because the wick carrier is positively guided by and between the longitudinal ribs 22 that are spaced apart circumferentially of the outer wick tube 2, and is lifted at diametrically opposite points so as to avoid any tilting or binding tendencies; and moreover, should there be any variation in the sizes of wick carriers, which not infrequently happens, the outer wick tube will adjust itself thereto by yielding inwardly slightly between the ribs. The ribs, as will be seen from Fig. 1, stop short of the lower end of the tube and terminate at their upper ends a considerable 115 distance below the upper end of the tube. 120

The wick elevator or yoke is adapted to be moved vertically within the wick space by means of a rod 25 which has its lower end connected to the arm 17 preferably by reducing it at 26 for insertion through an aperture 27 in the top wall of the arm and further at 28 for extension through a smaller 130

aperture in the lower wall of the arm beyond which it is upset or riveted, as indicated at 29 in Fig. 2. At its upper end, the rod 25 is guided within a sleeve 30 that 5 forms an extension of the restricted offset portion 8 and which rises from the top wall thereof, the inner wick tube being cylindrical above said offset portion, as indicated at 1^a. The rod 25 terminates at its upper end 10 in a head 32 which is separated from the body portion of the rod by a neck 33.

A rack member 35, preferably of sheet metal and of channel formation, is adapted to have connection with the rod 25 through 15 its extended side flanges 36 and 37. The connection is preferably effected by engaging the inturned bifurcated upper end 39 of the flange 37 about the neck 33 of the rod, and the key-hole slot 40 that is formed in 20 the inturned upper end of the flange 36 over the head 32 and shifting it laterally so as to cause the restricted end of the slot to embrace the neck, in which condition the parts 25 may be securely held by turning a tongue 41 of the flange 36 downwardly over the flange 37 and engaging it through an aperture 42 that is formed therein, as clearly shown in 30 Fig. 2. One of the side flanges of the member 35 is provided with a series of slots 43 which extends upwardly a suitable distance from its lower end to effect a rack.

Arranged to mesh with the rack is a pinion 45 that is secured to a spindle 46. The spindle is journaled in bearing apertures in the opposite branches 47 and 48 of a bracket 49 that is secured to and depends from the lower end of the burner. The forward end of the spindle is equipped with a hand wheel 50 by means of which the spindle 40 may be turned; and from the foregoing description it is evident that when the spindle is turned it will move the rack member 35 vertically, and said movement will be transmitted through the rod 25 to the wick elevator or yoke 10.

A pair of wick grips 55, that are preferably formed of spring brass or other suitable resilient metal, have their lower ends shaped to extend about and interlock with the extensions 12 of the yoke 10, the parts being soldered or otherwise secured together after being thus assembled. The grips 55 are formed at their upper ends with diverging branches which are flanged inwardly to provide lips 57. The wick 60 which is provided with the usual wick carrier 61 that encases the lower portion of the wick and is turned inwardly and upwardly about its lower end, is adapted to bear upon the horizontal portions of the extensions 12 and to fit between the vertical portions thereof and the opposed parts of the grips 55. With the wick in this position the upper end of its carrier is engaged beneath the lips 57 of the 65 grips 55. To insert a wick within the burn-

er, the elevator is raised to its highest position when the grips 55 will protrude above the wick tubes and through their resiliency and formation spread out considerably. See Fig. 8. The wick is then lowered into the 70 wick space until the bottom of its carrier engages the horizontal portions of the extensions 12. The spindle 46 is now rotated in a direction to lower the elevator, and as it and the wick descend the grips 55 are forced 75 inwardly by contact with the outer wick tube to engage their lips 57 over the upper edge of the wick carrier. When the yoke 10 is elevated to its highest position the grips 80 will automatically separate to release the carrier so that the wick and carrier may be lifted bodily from the burner.

Situated to the rear of and guided within the rear branch 48 of the bracket 49 is wick stop mechanism designated generally by the letter D and fully disclosed in the application of Lee S. Chadwick, Serial No. 528,813 hereinbefore referred to. This mechanism, as will be seen by reference to said application, coacts with the wick adjusting spindle 90 to arrest the movement of the wick when the same has been elevated to a predetermined height, and it includes the air controlling member or flame spreader B through the intervention of which said mechanism is 95 coupled with the wick raising spindle when said member is engaged and lifted by the burned portion of the wick, the mechanism further serving to lift the flame spreader to 100 operative position when the wick occupies any position within its burning range.

To conceal those parts of the wick stop mechanism which extend below the burner tubes and to protect them against being tampered with unnecessarily we provide a shield 65, the upper end of which is shown as notched at 66 to accommodate the side flanges of the bracket 49, and at 67 to accommodate the spindle 46. The shield may be inserted between the rear branch 48 of the bracket 49 and the lower end of the rack member 35 only when the rack member is 110 fully elevated. After its upper end is so engaged between these parts, its lower end may be swung rearwardly to project the lugs 68 beneath the lower end of the rear branch 48 of the bracket and engage a spring tongue 70 between the lugs 68 and in holding engagement with the adjacent edge portion of the shield 65. The tongue 70 which serves to frictionally hold the shield in place, may be formed by an extension of a brace 71 that connects the lower end of the bracket to the rear portion of the burner. It will thus be seen that the shield may be readily 125 removed for the purpose of inspecting, adjusting or repairing the parts which it normally conceals, by releasing its lower end from the spring tongue 70 and dropping it.

A modification of the wick grip is illus-

trated in Fig. 9 which is distinguished from the previously described form by providing its inwardly directed upper edge portions 75 with prongs or teeth 76 which are shown 5 as strengthened by beads 77. The grip, as a whole, is designated 55^a.

For use with the modified form of the wick grip illustrated in Fig. 10, and designated 55^b, is a wick carrier 78 having a circumferential series of rectangular openings 79 adjacent its upper edge through which prongs 80 of the grip are adapted to be engaged, the several prongs being so disposed as to fit between the top and bottom edges of 15 the openings so as to restrain the carrier against any appreciable vertical movement with respect to the wick grips.

In both forms of the wick grip illustrated in Figs. 9 and 10 the action is automatic in 20 taking hold of and releasing the wick, the upper edge of the outer wick tube serving to cam the grips inwardly as the parts are retracted, while the form and resiliency of the grips causes them to withdraw from 25 the wick as the parts are projected above the outer wick tube.

The upper end of the wick grip 55^c illustrated in Fig. 11, is turned laterally and the upper edge of the laterally turned portion 30 is shown as provided with teeth 82 for engagement over the top edge of the wick carrier and insertion into the material of the wick, with this form of the grip, when the parts are fully projected for the 35 purpose of removing or inserting a wick the laterally extended upper end of the grip springs out over the top edge of the outer wick tube and tends to hold the parts against retraction. This is done in order to compel 40 the operator to press the expanded laterally turned portions of the grips inwardly into holding engagement with the wick and carrier before the grips are permitted to descend in order to insure that the grips will 45 be properly engaged with the carrier; for it might happen occasionally in the previously described forms that the grips would descend in advance of the wick and would not engage over the top of the carrier. However, the former automatically acting grips 50 have proven highly satisfactory.

The same principle is involved in the grip 55^d that is illustrated in Fig. 12. The grip is provided along its upper edge with teeth 84, and a detent 85, preferably bearing the word "Press" or some equivalent expression, is struck out from the metal whereof the grip is formed and is sprung outwardly beyond the plane thereof so as to engage the 60 top edge of the outer wick tube and arrest downward movement of the parts until the detents of the opposed grips are pressed inwardly to escape the top of the wick tube, which action results in the prongs 84 being 65 engaged over the top of the carrier.

The grip 55^e, shown in Figs. 13 and 14, is quite similar to the one just described, the same being equipped with teeth 86 for engagement over the top edge of the carrier and with the wick, and with a spring detent 70 87 that is struck out from the metal from which the grip is made and has its lower free edge provided with prongs 88 which are adapted to be engaged within the perforations of the wick carrier when the detent 75 is pressed inwardly to escape the edge of the outer wick tube and to engage the teeth 86 over the carrier and with the wick.

In Figs. 15 and 16 are shown grips 55^f and 55^g, respectively, which are quite similar to the grip illustrated in Fig. 11. The grip 55^f has a series of inwardly directed projections 90 and the grip 55^g, an inwardly directed depression 91, formed in their respective body portions, which frictionally engage the wick carrier, and, in each instance, drag it downwardly when the elevator descends causing the wick and carrier to move in unison with the elevator, thus insuring the wick and carrier to move in 90 unison with the elevator thus insuring the proper engagement of the teeth of the grip over the upper edge of the carrier and into the wick.

To adapt it for use with the form of 95 grip designated 55^h in Figs. 17 and 18, the wick carrier has a series of apertures 94 extending circumferentially about its upper end into ones of which the expanding portions 95 of the grips are adapted to be 100 snapped, the parts coacting much like the ordinary glove fastener. Thus, in this form of the invention, a positive connection between the grips and carrier is immediately effected.

Having thus described my invention, what I claim is:

1. In a burner of the character set forth, the combination of a structure enclosing a wick space and having a lateral offset portion extending upwardly along one side of the structure and opening throughout substantially its height into the wick space, a wick within the wick space, a member guided for vertical movement by and within the lateral offset portion of the structure, connections between said member and the wick, a member slideable upon the exterior of and thus guided by the lateral offset portion and having its upper end attached to the corresponding end of the aforesaid member, and means exterior of the burner structure for adjusting the wick through the intervention of said members.

2. In a burner of the character set forth, the combination of a structure enclosing a wick space and having a lateral offset portion extending upwardly along one side of the structure and opening throughout substantially its height into the wick space, a 125

wick within the wick space, a member movable vertically within the lateral offset portion of the structure, connections between said member and the wick, a rack member 5 of channel formation embracing the lateral offset portion and having its upper end attached to the corresponding end of the aforesaid member, a spindle rotatably supported by the structure, and a pinion secured to 10 the spindle and cooperating with the rack member.

3. An oil burner comprising an inner and an outer wick tube and wick stop mechanism occupying the central portion of the 15 space enclosed by the inner wick tube, said inner wick tube having an inwardly offset portion situated to one side of the central portion of said space, a wick occupying the space between the wick tubes, and 20 exteriorly operated means acting through said offset portion for raising and lowering the wick.

4. An oil burner comprising an inner and an outer wick tube enclosing an annular wick 25 space between them, the inner wick tube having an inwardly offset portion, a wick elevator extending part way around the wick space, a tubular wick in the wick space, said wick having connection at diametrically opposite points with the elevator, and exteriorly operated means acting through said 30 offset portion for raising and lowering the wick.

5. In a burner of the character set forth, 35 the combination of an inner and an outer wick tube enclosing a wick space between them, one of said tubes having an offset portion, a member movable vertically within said offset portion, a wick within the wick space, a segmental wick elevator below the wick and having at about its middle a lateral extension projecting into the aforesaid offset portion, the lateral extension being connected to the aforesaid member, wick 40 grips carried by the ends of the elevator for separably connecting it to the wick at diametrically opposite points, and means for adjusting the aforesaid member vertically thereby to raise and lower the wick.

6. In a burner of the character set forth, 45 the combination of an inner and an outer wick tube enclosing between them an annular wick space, one of said tubes having a lateral offset portion, a member movable vertically within said offset portion, a tubular wick within the wick space, a carrier 50 on the wick, a segmental wick elevator extending substantially half way about the wick space and having at about its middle a lateral arm extending into the aforesaid offset portion where it is attached to the aforesaid member, wick grips carried by the elevator for effecting separable connection 55 between the wick elevator and the carrier wick, and means for adjusting the aforesaid 60

member vertically thereby to raise and lower the wick.

7. In a burner of the character set forth, the combination of an inner and an outer wick tube enclosing between them a wick 70 space, a wick elevator within the wick space, a wick and its carrier adapted to be inserted into the wick space and rest upon the wick elevator, resilient grips extending upwardly from the wick elevator and adapted 75 to embrace the wick carrier and means for adjusting the wick elevator vertically to raise and lower the wick.

8. In a burner of the character set forth, the combination of an inner and an outer wick tube enclosing between them an annular wick space, one of said tubes having an offset portion, a member movable vertically within said offset portion, a wick elevator 80 extending substantially halfway around the wick space and having at about its center a lateral arm that projects into the aforesaid offset portion where it has connection with the said member, a wick and its carrier adapted to be inserted into the wick 85 space and rest upon the wick elevator, resilient grips extending upwardly from the ends of the wick elevator and adapted to be forced into holding contact with the wick carrier by the outer wick tube when the 90 parts are retracted into the wick space, and means for adjusting the aforesaid member vertically thereby to raise and lower the 95 wick.

9. In a burner of the character set forth, 100 the combination of an inner and an outer wick tube enclosing between them an annular wick space, the inner tube having a radially disposed offset portion, a rod movable vertically within said portion, a wick 105 elevator extending substantially half-way about the wick space and having a central lateral extension projecting into the aforesaid offset portion of the inner wick tube and connected to the aforesaid rod, the wick 110 elevator having at its ends raised bearing portions, resilient wick grips secured to and rising from the opposite ends of the wick elevator and having inwardly directed lips 115 at their upper ends, a wick and its carrier adapted to be inserted into the wick space with the carrier resting upon the aforesaid portions of the elevator while the inwardly directed lips of the wick grips engage over the upper edge of the wick carrier, and means for adjusting the aforesaid member vertically thereby to raise and lower the 120 wick.

10. In a burner of the character set forth, 125 the combination of an inner and an outer wick tube enclosing between them an annular wick space, the inner wick tube having a substantially radial inward extension thereby to provide an offset of the wick space, a rod movable vertically within the 130

offset, a segmental wick elevator within the wick space and having a central lateral extension projecting into the offset and having connection with the rod, the offset and lateral extension having cooperating guide portions for properly positioning the elevator within the space during its vertical movements therewithin, an annular wick within the wick space, means separably connecting the wick and elevator, and means for adjusting the aforesaid rod vertically within the offset thereby to raise and lower the wick.

11. In a burner of the character set forth, the combination of an inner and outer wick tube enclosing between them an annular wick space, the inner tube having a substantially radially disposed inward projection to provide an offset for the wick space, a rod movable vertically within the offset, a wick elevator extending part way around the wick space and having a lateral extension projecting into the offset and having connection with the rod, a wick within the wick space, means separably connecting the wick and elevator, a channel shaped rack member embracing the radial extension of the inner wick tube and having its upper end connected to the corresponding end of the aforesaid rod, a spindle rotatably supported below the wick tubes, means for rotating the spindle, and a pinion on the spindle for co-operation with the aforesaid rack member.

12. In a burner of the character set forth, the combination of a structure enclosing a wick space and having a comparatively narrow lateral extension the interior whereof opens into the wick space, a rod movable vertically within the lateral extension, a wick within the wick space, connections between the wick and the lower end of the aforesaid rod, the upper end of said rod projecting above the lateral extension and terminating in a head, a channel member embracing the lateral extension and having extended side flanges which terminate at their upper ends in inwardly directed lug, one having a key hole slot and the other a bifurcation, the bifurcation being engaged beneath the head of the rod and the restricted portion of the key hole slot embracing the rod immediately below the head, the lug having the key hole slot being provided with a tongue and the flange extension having the bifurcation being provided with an aperture through which the tongue is engaged thereby to securely hold the parts together, and means for adjusting the channel member vertically thereby to raise and lower the wick.

13. In a burner of the character set forth, the combination of a structure enclosing a wick space and having a lateral extension the interior whereof opens into the wick space, a rod movable vertically within the lateral extension, a wick within the wick

space, connections between the wick and the lower end of the rod, the upper end of said rod projecting above the lateral extension and having longitudinally spaced abutments, a member extending up along side the lateral extension and having opposed parts which embrace the rod between said abutments and interlock with each other to hold them in position, and means for adjusting the channel member vertically thereby to raise and lower the wick.

14. A connection of the character described comprising a rod having longitudinally spaced abutments, and a member adapted to be connected to said rod and having opposed resilient branches terminating at their ends in parts designed to embrace the rod between said abutments and interlock with each other to hold them against separation.

15. A connection of the character described comprising a rod having at one end a shoulder beyond which projects a neck that terminates in a head, and a member adapted to be connected to said rod and having opposed resilient branches terminating at their ends in inwardly directed lugs, one of said lugs having a key hole slot and terminating in a tongue, while the other lug is bifurcated, the bifurcation of the last mentioned lug being arranged to embrace the neck of the rod adjacent the shoulder and the lug having the key hole slot being adapted to be turned down over the head and shifted laterally so that the neck will be embraced by the restricted portion of the slot, the branch having the bifurcated lug being provided with an aperture through which the tongue of the other lug is adapted to be turned for the purpose of holding the parts in assembled condition.

16. In a burner of the character set forth, the combination of a structure enclosing a wick space and having a lateral extension the interior whereof opens into the wick space, a rod within the lateral extension, a wick within the wick space, connections between the rod and wick, the upper end of the rod projecting above the lateral extension and there being formed with a groove to provide opposed abutments spaced apart longitudinally of the rod, a channel member embracing the lateral extension and having its side flanges extended and turned inwardly at their upper ends and provided with openings for interlocking engagement with the rod between the aforesaid abutments, and means for adjusting the channel member vertically thereby to raise and lower the wick.

17. In a burner of the character set forth, the combination of a structure enclosing a wick space and having a lateral extension the interior whereof opens into the wick space, a rod within the lateral exten-

- 5 sion, a wick within the wick space, connections between the rod and wick, the upper end of the rod projecting above the lateral extension and there being formed with a groove to provide opposed abutments spaced apart longitudinally of the rod, a channel member embracing the lateral extension and having its side flanges extended and turned inwardly at their upper ends and 10 provided with openings for interlocking engagement with the rod between the aforesaid abutments, one of the flange extensions having a part cooperating with the other flange extension to hold them against separation, and means for adjusting the channel member vertically thereby to raise and lower the wick.
- 15 18. In a burner of the character set forth, the combination of a structure enclosing a wick space and having a lateral extension the interior whereof opens into the wick space, a wick within the wick space, a rod within the lateral extension and having its lower end reduced, a sheet metal wick elevator within the wick space below the wick and having an arm projecting into the lateral extension and provided with an aperture through which the reduced lower end of the rod is extended, a stiffener for the 20 wick elevator applied to the underneath side thereof and having an arm corresponding to that of the elevator and provided with an aperture through which the extremity of the rod is extended and beyond which it is 25 riveted to hold the parts together, and means for adjusting the rod vertically thereby to raise and lower the wick.
- 30 19. In a burner of the character set forth, the combination of a structure enclosing an annular wick space, a tubular wick within said space, a wick elevator within the wick space sustaining the wick, means for adjusting the elevator vertically within the wick space, the ends of the elevator terminating 35 in angle portions having vertical and horizontal flanges, the latter constituting seats for the wick, and wick grips having their lower ends extending under the horizontal flanges and upwardly over and downwardly alongside the vertical flanges, as and for the purpose specified.
- 40 20. In a burner of the character set forth, the combination of an inner and an outer wick tube enclosing between them a wick space, a wick elevator within the wick space, a wick and its carrier adapted to be inserted into the wick space and to rest upon the wick elevator, wick grips of resilient material extending upwardly from the wick elevator and terminating at their upper ends in lateral branches which are normally substantially tangentially disposed to the wick carrier so as to expand beyond the upper end of the outer wick tube and which have 45 at their upper edges means for engaging over the top of the wick carrier, whereby the wick elevator is prevented from descending into the wick space until said lateral branches are pressed inwardly to escape the outer wick tube and engage the aforesaid means over the top of the wick carrier, and means for adjusting the wick elevator vertically, thereby to raise and lower the wick.
- 50 21. In a burner of the character set forth, the combination of a structure enclosing a wick space, a wick within the wick space, a member guided for vertical movement within the wick space and having its upper end extending without the wick space above the maximum oil level therein, connections between said member and the wick, a member exterior of the wick space and having its upper end attached to the corresponding end of the aforesaid member, and means exterior of the burner structure and cooperating with the lower portion of the second mentioned member for adjusting the wick through the intervention of said members.
- 55 22. In a burner of the character set forth, the combination of a structure enclosing a wick space, a wick and its carrier within the wick space, a member guided for vertical movement by and within the wick space, a wick elevator supporting the wick carrier and holding it firmly at both top and bottom, said wick elevator being connected to the aforesaid member, and means exterior of the burner structure for adjusting the wick through the intervention of said member and the wick elevator.
- 60 23. In a burner of the character set forth, inner and outer wick tubes, a wick and carrier between the tubes, a rack and pinion located below the burner, means connecting the rack to the wick and carrier, said means including a movable member, guiding means positively restricting said member to a vertical course of movement, said member being positively connected to the wick and carrier when the carrier is retracted into the space between the tubes and said member automatically freeing itself from the wick and carrier when the top of the carrier is projected above the tubes.
- 65 24. An oil burner comprising an inner and an outer wick tube, said inner wick tube having an inwardly offset portion situated to one side of the center of the tube, a wick occupying the space between the wick tubes, and exteriorly operated means acting through said offset portion for raising and lowering the wick.
- 70 25. In a burner of the character set forth, inner and outer wick tubes, a wick between the tubes, a carrier on the outside of the wick, the outer tube having inwardly depressed longitudinal ribs that are spaced a

material distance apart circumferentially of the tube for guiding the carrier, and means for moving the carrier.

26. In a burner of the character set forth, 5 an inner wick tube, a wall spaced outwardly therefrom to provide an oil chamber between the wall and tube, a wick and carrier within the oil chamber, a rack and pinion outside the oil chamber, means for rotating 10 the pinion, means situated above the maximum oil level of the chamber and connecting the rack to the wick carrier so that rotary motion of the pinion will impart vertical movement to the wick carrier, and further means to prevent tipping or tilting 15 of the wick carrier during its vertical movement.

27. An oil burner comprising an inner and an outer wick tube, said inner wick tube 20 having an inwardly offset portion situated to one side of the center of the tube, a wick and carrier occupying the space between the

wick tubes, exteriorly operated means acting through said offset portion for raising and lowering the wick and carrier, and means to 25 guide the carrier and prevent tipping or tilting when the carrier is raised or lowered.

28. In a burner of the character set forth, the combination of an inner and an outer wick tube enclosing between them a wick 30 space, a wick elevator within the wick space, a wick and its carrier adapted to be inserted into the wick space and rest upon said wick elevator, wick grips carried by the elevator 35 separably connecting the wick and carrier to the elevator, means for adjusting the wick elevator vertically thereby to raise and lower the wick, and ribs in the tube adjacent the wick carrier for guiding the carrier in its movements. 40

In testimony whereof, we hereunto affix our signatures.
